A detailed black and white line drawing of a brilliant-cut diamond. The diamond is oriented vertically, with its pointed base at the bottom and its flat top at the top. The drawing illustrates the intricate facets and facets of the brilliant cut, which is a modified version of the older brilliant cut. It features a large, central, octagonal-shaped table surrounded by numerous smaller facets. The girdle, the middle band of the diamond, is also clearly defined. The pavilion, the bottom portion of the diamond, shows the deep, triangular facets that allow light to be reflected back up through the diamond. The overall effect is one of precision and mathematical beauty.
